UNITED STATES PATENT OFFICE.

WILLIAM F. STAGGERS, JR., OF MANNINGTON, WEST VIRGINIA.

SWAB-VALVE.

1,191,845.

Specification of Letters Patent. Patented July 18, 1916.

Application filed April 29, 1916. Serial No. 94,444.

To all whom it may concern:

Be it known that I, WILLIAM F. STAGGERS, Jr., a citizen of the United States, residing at Mannington, in the county of Marion and State of West Virginia, have invented new and useful Improvements in Swab-Valves, of which the following is a specification.

This invention relates to oil well swabs and more particularly to a swab valve 10 adapted to open and relieve the swab when the weight of the oil above the swab becomes more than a predetermined amount.

The swabs now in general use for bailing oil wells have but one valve in the form 15 of a check so that it is difficult to bail an equal amount of oil on each reciprocation of the swab and at times the swab will admit more oil above it than it can bail, which usually takes considerable time to remove. 20 It is the object of this invention to provide a relief valve in addition to the check valve in the swab which will allow the swab to bail uniformly and relieve any additional weight above the swab.

25 While the preferred form of this invention is illustrated upon the accompanying sheet of drawing, yet it is to be understood that minor detail changes may be made without departing from the scope thereof.

30 The figure is a central, sectional view of this improved device, illustrating in dotted lines the valve in the relief position.

The usual swab construction includes a central, depending tube through which the 35 oil enters and in carrying out this invention a combined check and relief valve is mounted in a tubular casing 1 adapted to be threaded on the end of the swab 2. The upper portion of the casing is slightly enlarged and is provided with an internal shoulder 3 at the lower termination of the 40 enlargement 4. The sides of the casing are provided with a plurality of elongated, longitudinal passageways 5 for the passage of oil in both directions. The lower end of the 45 casing is screw-threaded and is closed by threaded cap 6 preferably having a central opening therethrough.

A check valve seat 7 is slidably mounted 50 within the casing and is adapted to seat against the internal shoulder 3. A check

valve 8 is mounted to seat upon the upper surface of the seat 7 with a depending threaded stem 9 passing through a guide 10 spaced apart from and carried upon the 55 under side of the valve seat 7 having a portion extending to the sides of the casing for guiding the seat 7 and cut out for the passage of oil therethrough. The stem 9 is provided with an adjustable stop nut 11 for 60 limiting the upward movement of the check valve 8, so that when open the check valve will assume a position about the middle of the enlarged portion 4 of the casing.

A coil spring 12 is arranged between the 65 seat guide 10 and bottom casing closure 6 normally maintaining the check valve seat in seated engagement with the shoulder 3. The tension of this spring may be regulated by adjustment of the bottom closure 6, so 70 that when the weight of oil above the swab upon an upward stroke thereof is greater than a predetermined amount the check valve and check valve seat will be depressed and act as a relief valve for the swab. The 75 tops of the longitudinal openings preferably terminate at the bottom of the seat 7 so that only a slight depression of the check and check valve seat will relieve the swab.

What I claim is:—

80 In an oil well swab, a combined check and relief valve therefor comprising a casing carried upon the swab having passageways in the walls thereof and an internal shoulder thereabove, a check valve seat slidably 85 mounted within the casing, a check valve thereabove having a depending stem, a spaced apart guide carried upon the under side of the seat guiding the stem and seat, a stop upon the valve stem below the guide, 90 and an adjustable spring between the guide and bottom of the casing normally maintaining the check valve seat in seated engagement with the shoulder and allowing a movement thereof to uncover the casing wall 95 passageways upon excessive weight above the check valve.

WILLIAM F. STAGGERS, JR.
